UNITED STATES PATENT OFFICE.

HENRY A. HART, OF FLUSHING, NEW YORK, ASSIGNOR TO THE GIBSON ART COMPANY, OF NEW YORK, N. Y., A CORPORATION OF OHIO.

CUT-OUT ROCKING TOY.

1,255,743.

Specification of Letters Patent.

Patented Feb. 5, 1918.

Application filed May 1, 1917. Serial No. 165,667.

To all whom it may concern:

Be it known that I, HENRY A. HART, a citizen of the United States, and a resident of the city of New York, Flushing, borough of Queens, in the county of Queens and State of New York, have invented a new and Improved Cut-Out Rocking Toy, of which the following is a full, clear, and exact description.

10 This invention relates to toys known as "cut-outs," and relates particularly to a rocking toy.

The invention has for its general objects to provide a simple, novel and entertaining 15 toy or cut-out which is comparatively inexpensive to manufacture and which a child can readily construct, the toy embodying a body and base which are separately cut out from a piece of cardboard or equivalent material on which the design is printed or otherwise delineated.

20 A more specific object is the provision of a toy embodying a body and base and having novel means for detachably connecting 25 the two parts to form a unitary article which can oscillate on a table or other surface by a gentle motion being imparted to the toy.

With such objects in view, and others 30 which will appear as the description proceeds, the invention comprises various novel features of construction and arrangement of parts which will be set forth with particularity in the following description and 35 claims appended hereto.

40 In the accompanying drawing, which illustrates one embodiment of the invention and wherein similar characters of reference indicate corresponding parts in all the views, Figure 1 is a plan view of a card or sheet from which the toy is cut out, the two sections of the toy being printed or otherwise delineated thereon;

45 Fig. 2 is a front view of the toy completed; and

Fig. 3 is a vertical section on the line 3—3 Fig. 2.

50 Referring to the drawing, 1 designates a card on which is printed with a depicted outline, the body and base sections A and B, respectively, of the toy. The user is intended to cut out these two sections along the full and dot-and-dash outline. The bottom edge

of the body section A is provided with depending lugs 2 which are always in the same 55 plane with the body. On the front surface of the body is a picture and the outline may represent one or more figures or forms to amuse or entertain a child.

The base B is approximately elliptical and 60 is adapted to be folded on the lines 3 and 4 which are parallel with the major axis of the base and at opposite sides thereof. When thus folded the base is composed of front and rear rockers 5 and 6 and a connecting 65 top plate 7. The line of fold 3 is slit at three points 8, so as to receive the three lugs 2 of the body section. The front face of the front rocker is printed or otherwise delineated to form a continuation of the picture 70 on the front of the body A. The lugs are concealed behind the front rocker so that they will not be seen when the toy is viewed from in front. The two rockers will support the toy upright and allow it to have a 75 general back and forth rocking motion when its center of gravity is shifted by the child applying a lateral force to the toy.

From the foregoing description taken in connection with the accompanying drawings, 80 the advantages of the construction and method of operation will be readily understood by those skilled in the art to which the invention appertains, and while I have described the principle of operation, together 85 with the article which I now consider to be the best embodiment thereof, I desire to have it understood that the article shown is merely illustrative and that such changes may be made when desired as fall within the scope 90 of the appended claims.

Having thus described my invention, I claim as new and desire to secure by Letters Patent:

1. An article of the class described comprising a body section, a rocker base section consisting of a double folded sheet piece with the folds spaced from each other, and means for detachably connecting the sections.

2. A cut-out rocking toy comprising a body section having depending lugs at its bottom, and a rocker base having apertures in its top for receiving the said lugs.

3. A cut-out rocking toy comprising a flat body section having a lug and a base

section formed of a flat piece having two parallel folds and curved opposite edges, whereby the outer portions constitute rockers, and an aperture in the base section for receiving the lug of the body section.

4. A rocking toy comprising a base section formed of a folded piece of material and em-

bodying front and rear rockers and a top connecting portion, apertures in the line of fold between one of the rockers and the top connecting portion, and a body having lugs at its lower edge engaging in the apertures.

HENRY A. HART.
